UNITED STATES PATENT OFFICE

97,025

DESIGN FOR LACE

James Waterfield, Philadelphia, Pa., assignor to Quaker Lace Company Inc., Philadelphia, Pa.

Application April 26, 1935, Serial No. 56,566

Term of patent 3½ years

To all whom it may concern:

Be it known that James Waterfield, a citizen of the United States, residing at 5333 Wakefield Street, Philadelphia, in the county of Philadelphia and State of Pennsylvania, has invented a new, original, and ornamental Design for Lace, of which the following is a specification, reference being had to the accompanying drawing, forming a part thereof, in which the figure is a face view of a section of the lace showing my new design, the other sections being identical with that here disclosed, arranged in proper relation to complete the width and length of the lace.

I claim:—

The ornamental design for lace substantially as shown and described.

In testimony whereof I affix my signature.

JAMES WATERFIELD.
